Primary Examiner—T. Chase Nelson*Assistant Examiner*—Karen Acker*(74) Attorney, Agent, or Firm*—Wenderoth, Lind & Ponack, L.L.P.(57) **CLAIM**

The ornamental design for sheet material, as shown and described.

DESCRIPTION

The sole FIGURE is a plan view of sheet material.

The broken line around the design indicates that a specific length and width forms no part of the claimed design and that the pattern upon the sheet material repeats uniformly throughout the length and width of the sheet material. The broken line forms no part of the claimed design.
